IMPROVED MACHINE FOR SCOURING LEATHER.

FRANKLIN DAVIS, OF LAWRENCE, KANSAS.

Letters Patent No. 60,149, dated December 4, 1866.

SPECIFICATION.

TO ALL WHOM IT MAY CONCERN:

Be it known that I, FRANKLIN DAVIS, of Lawrence, in the county of Douglas, and State of Kansas, have invented a new and improved Machine for Scouring Leather; and I do hereby declare that the following is a full, clear, and exact description thereof.

This invention consists in constructing a machine by which the tedious and expensive process of scouring leather shall enable me to accomplish the operation by the use of power, either water, steam, or horse power, in a much more rapid, cheap, and perfect manner than it has been done hitherto; and the machine consists principally of a frame, a cylinder, apron, and water reservoir.

To enable others skilled in the art to make and use my invention, I will proceed to describe its construction and operation, reference being had to the accompanying drawings forming part of this specification, and to the letters of reference marked thereon, in which—

Figure 1 represents a side elevation; and

Figure 2, a top or plan view partly sectional.

The same letters of reference indicate like parts.

A represents the frame; B, the cylinder; C, the apron; and D, the water reservoir. I construct a strong frame of suitable size, the back posts of which are longer and extend up higher than the front ones, for the purpose of receiving and supporting the back end of the apron. The sides of this frame support the cylinder. The apron is formed of two side pieces C', which are connected by a simple loose joint to the back posts in such a manner as to allow the front portion to be elevated and depressed at the will of the operator, as seen in dotted lines at e, these back posts being made broad to receive them. Two cross-pieces, E, connect these sides together. The under side of this apron, from the front to the back cross-piece, is covered with leather. The apron is sufficiently wide between the side pieces for the purpose intended, or to admit any side of leather. The cylinder B may be a foot, or more, in diameter, and must be sufficiently long to allow the apron to rest over it and be pressed upon it, it being about the length of the cross-piece E, or the width of the apron on the inside. It has journals at each end, upon which it revolves, and a pulley at one end, by which it is driven. It is made to revolve rapidly. I have found about three hundred and fifty revolutions per minute to be about right. To make this a scouring cylinder, rows of scouring stones are inserted lengthwise. I have found four rows to be sufficient, but there may be more or less. They do not stand on a line across the length of the cylinder, but run spirally across, as seen in fig. 2. They are of such a width that about five of them will reach across the cylinder, and of a thickness sufficient to give them the required strength to stand the friction to which they are subjected. These scouring stones project from the surface or periphery of the cylinder as far as may be desirable. The water reservoir D is placed back and a little above the centre of the cylinder in the drawing, but it may be located in any position where streams of water can be discharged from it on to the cylinder, and it may be constructed in any suitable manner. The little pipes a are in connection with this water reservoir. J is a spring attached to the inside of the frame at the right hand of the tender, and is so placed that it will hold up the apron above the cylinder when it is in motion, but not at work.

The operation is as follows: The cylinder being put in motion, the man in attendance throws one end of a side of leather (g in the drawing) over the top of the apron; the end dropping down and hanging from the back cross-piece, is immediately caught by the stones of the revolving cylinder and brought forward towards the tender, as seen in the drawing. The apron now rests upon the cylinder, and the tendency of the cylinder is to draw the side of leather through and drop it at the feet of the tender; but he holds on to it, and feeds it through, while the stones scour it as much as he desires. The side of leather being in contact with the elastic leather bottom of the apron, is thereby adjusted to the face of the scouring stones, and receives an even dressing in every part. The water from the reservoir being at the same time discharged from the pipes a upon the cylinder, assists in the operation.

Having thus described my invention, what I claim as new, and desire to secure by Letters Patent, is—

The cylinder B and the apron C, constructed, arranged, and operating substantially as described, in combination with the frame A and the water reservoir D, for the purposes set forth.

FRANKLIN DAVIS.
